HALOGENATED ORGANIC COMPOUNDS

Murray Hauptschein, Glenside, and Milton Braid, Philadelphia, Pa., assignors to Pennsalt Chemicals Corporation, Philadelphia, Pa., a corporation of Pennsylvania
No Drawing. Filed Jan. 11, 1960, Ser. No. 1,440
4 Claims. (Cl. 260—653)

This invention relates to the preparation of the iodide 1,1,2-trichloro-2,2-difluoro-1-iodoethane.

In accordance with the invention it has been found that when iodine monochloride (ICl) is reacted with the olefin $\text{CF}_2=\text{CCl}_2$ products of the general formula $\text{C}_2\text{F}_2\text{Cl}_3\text{I}$ are produced.

It has been found that these products consist, under normally chosen reaction conditions, of a mixture of isomers having substantially the same boiling point, namely the isomer 1,1,2-trichloro-2,2-difluoro-1-iodoethane, $\text{CF}_2\text{ClCCl}_2\text{I}$ and the isomer 2,2,2-trichloro-1,1-difluoro-1-iodoethane, $\text{CCl}_3\text{CF}_2\text{I}$. As will be pointed out more in detail hereafter, the isomer $\text{CF}_2\text{ClCCl}_2\text{I}$ is an excellent telogen or chain transfer agent for carrying out telomerization reactions involving reactive olefins such as $\text{CF}_2=\text{CFCI}$ and $\text{CF}_2=\text{CF}_2$ while the isomer $\text{CCl}_3\text{CF}_2\text{I}$ is, relative to the former isomer, a very poor chain transfer agent for this purpose. It has also been found that under normally chosen reaction conditions a substantial proportion of iodide or olefin is chlorinated to the compound $\text{CF}_2\text{ClCCl}_3$ instead of being converted to the desired iodide.

In accordance with the invention it has been found that the isomer $\text{CF}_2\text{ClCCl}_2\text{I}$ may be prepared, while producing little or substantially none of the undesired isomer $\text{CCl}_3\text{CF}_2\text{I}$ by reacting iodine monochloride with the olefin $\text{CF}_2=\text{CCl}_2$ at low temperatures, namely, temperatures ranging from -20° C . to $+15^\circ\text{ C}$. and preferably from -10° C . to $+10^\circ\text{ C}$. At these temperatures less than 5%, and at the preferred temperatures less than 0.5% of the isomer $\text{CCl}_3\text{CF}_2\text{I}$ appears in the reaction products. At temperatures higher than $+15^\circ\text{ C}$. on the other hand, the amount of the undesired isomer $\text{CCl}_3\text{CF}_2\text{I}$ formed progressively increases. It has also been found at these low temperatures little or substantially none of the chlorinated by-product $\text{CF}_2\text{ClCCl}_3$ is produced while at higher temperatures the amount of this by-product progressively increases.

To prevent the formation of the isomer $\text{CCl}_3\text{CF}_2\text{I}$ it has also been found desirable to avoid the presence of iron in the reaction mixture in a form which is chemically attacked by the reaction mixture or products. Apparently, iron in this form, or more probably iron compounds formed by the attack of the reaction mixture upon the iron, acts as a catalyst for the formation of the undesired isomer $\text{CCl}_3\text{CF}_2\text{I}$. The presence of iron in a form that is not chemically attacked, such as the use of iron-containing alloy equipment is generally not detrimental. Thus, for example, a Monel metal autoclave, consisting predominantly of an alloy of nickel and copper and containing, e.g. 1 to 7% iron alloyed therewith may be employed.

According to the preferred method of carrying out the reaction, the olefin, which is a liquid at reaction temperatures (boiling point 19° C .) is cooled to the reaction temperature (e.g. 0° C .) an ice or an ice-brine bath being suitable for this purpose. Iodine monochloride (preferably as a liquid) is then added slowly to the liquid olefin while vigorously agitating the reaction mixture. Preferably agitation is continued for a period of e.g. 1 to 2 hours after addition of the iodine monochloride is completed.

In order to insure complete utilization of the iodine monochloride, and to avoid having to remove excess

2

iodine monochloride from the reaction mixture, the olefin is preferably used in stoichiometric excess in the reaction mixture. Molar ratios of olefin:ICl of from 3:1 to 1:1 and preferably from 1.3:1 to 1.1:1 will generally be found satisfactory. Following the reaction, unreacted olefin may be removed from the reaction mixture, for example by refluxing under reduced pressure.

The reaction is most conveniently carried out at atmospheric pressure, although pressure is not critical and elevated pressures may be employed if desired.

The reaction time is not critical. Depending somewhat upon the reaction temperature, reaction periods of from 5 hours to 1 minute and more usually from 2 hours to one-half hour are satisfactory.

In the event all of the iodine monochloride is not reacted, the unreacted ICl may be removed by washing with water, preferably by pouring the reaction mixture over crushed ice. The iodine monochloride decomposes into products soluble in the water layer, as well as solid iodine, which then may be separated from the product iodide.

The following examples illustrate the preparation of the iodide $\text{CF}_2\text{ClCCl}_2\text{I}$ and the effect of temperature upon the formation of the undesired isomer $\text{CCl}_3\text{CF}_2\text{I}$ and the undesired chlorination product $\text{CF}_2\text{ClCCl}_3$.

Example 1

166 grams (1.25 moles) of $\text{CF}_2=\text{CCl}_2$ is introduced into a glass flask cooled by means of an ice-brine bath to -10° C . 162 grams (1 mole) of iodine monochloride is added to the liquid olefin drop by drop while vigorously stirring over a period of one-half hour while maintaining the reaction mixture at -10° C . Stirring is continued for an additional two hours after which 35 grams of unreacted olefin is removed from the cold reaction mixture under reduced pressure.

The remaining product consists of 292 grams made up of 290 grams of the iodide $\text{CF}_2\text{ClCCl}_2\text{I}$ and 2 grams of $\text{CF}_2\text{ClCCl}_3$. The product is free from detectable traces of the undesired isomer $\text{CCl}_3\text{CF}_2\text{I}$.

The iodide $\text{CF}_2\text{ClCCl}_2\text{I}$ is a solid at room temperature, having a boiling point of 75° C . at 75 mm. Hg and a melting point of 35 to 37° C . The ultraviolet absorption maximum for $\text{CF}_2\text{ClCCl}_2\text{I}$ in isoctane is at 302 m μ .

Characteristic absorption bands in the infrared spectrum of $\text{CF}_2\text{ClCCl}_2\text{I}$ (vapor) are at 8.58, 9.8, 11.7, 11.8 (shoulder), 11.9 (shoulder), 13.0, and 14.5 microns. Analysis of this compound is as follows:

Calculated for $\text{C}_2\text{Cl}_3\text{F}_2\text{I}$: C, 8.1, Cl, 36.0. Found: C, 8.5, Cl, 36.6.

Example 2

To 300 grams (2.25 moles) of $\text{CF}_2=\text{CCl}_2$ in a glass flask cooled to 0° to $+3^\circ\text{ C}$. there is added drop by drop over a period of 3.5 hours 292.5 grams (1.8 moles) of iodine monochloride while stirring. Stirring is continued for another 2 $\frac{1}{2}$ hours after which the crude product is worked up to yield 14% weight percent of unreacted $\text{CF}_2=\text{CCl}_2$, 1 weight percent of $\text{CF}_2\text{ClCCl}_3$, 85 weight percent of $\text{C}_2\text{F}_2\text{Cl}_3\text{I}$. The iodide product $\text{C}_2\text{F}_2\text{Cl}_3\text{I}$ consists of 99% of the desired isomer $\text{CF}_2\text{ClCCl}_2\text{I}$ and 1% of the undesired isomer $\text{CCl}_3\text{CF}_2\text{I}$.

Example 3

To 300 grams (2.25 moles) of $\text{CF}_2=\text{CCl}_2$ in a glass flask cooled to $+15^\circ\text{ C}$. there is added drop by drop over a period of two hours 292.5 grams (1.8 moles) of iodine monochloride while stirring. Stirring is continued for another 2 $\frac{1}{2}$ hours after which the crude product is worked up to yield 9.2 weight percent of unreacted $\text{CF}_2=\text{CCl}_2$, 3.0 weight percent of $\text{CF}_2\text{ClCCl}_3$ and 87.8 weight percent of $\text{C}_2\text{F}_2\text{Cl}_3\text{I}$. The iodide product $\text{C}_2\text{F}_2\text{Cl}_3\text{I}$ consists of

98% of the desired isomer $\text{CF}_2\text{ClCCl}_2\text{I}$ and 2% of the undesired isomer $\text{CCl}_3\text{CF}_2\text{I}$.

Example 4

To 90 grams (0.55 mole) of iodine monochloride there is added with stirring 80 grams (0.602 mole) of $\text{CF}_2=\text{CCl}_2$ in a glass flask equipped with a reflux condenser for maintaining the reaction mixture at a temperature of about $+20^\circ\text{ C}$. There is obtained 150 grams of crude product. This product is analyzed by vapor-liquid partition chromatography and shown to consist of 72 mole percent (79 weight percent) of isomeric iodides $\text{C}_2\text{F}_2\text{Cl}_3\text{I}$ and 28 mole percent (21 weight percent) of by-product $\text{CF}_2\text{ClCCl}_3$. The isomeric iodides are analyzed and shown to consist of a mixture of 11% of the undesired isomer $\text{CCl}_3\text{CF}_2\text{I}$ and 89% of the desired isomer $\text{CF}_2\text{ClCCl}_2\text{I}$. Using a Perkin Elmer "B" chromatographic column 2 meters in length and operating at 100° C . under a pressure of helium of 30 lbs./in.² gage, the respective elution times for air, $\text{CCl}_3\text{CF}_2\text{I}$ and $\text{CF}_2\text{ClCCl}_2\text{I}$ are 0.55 minute, 43.5 minutes and 52 minutes respectively. The isomer $\text{CCl}_3\text{CF}_2\text{I}$ has a boiling point of 74° C . at 75 mm. Hg. The ultraviolet absorption maximum for $\text{CCl}_3\text{CF}_2\text{I}$ in isooctane is at $275\text{ m}\mu$. The respective structures of the two isomers is confirmed by their ultraviolet absorption maxima.

As may be seen from the results of the foregoing example, when the reaction was carried out at approximately room temperature, the isomeric content of

was 11% and 28 mole percent of the product consisted of by-product $\text{CF}_2\text{ClCCl}_3$. At higher reaction temperatures, the content of this undesired isomer and of the undesired by-product $\text{CF}_2\text{ClCCl}_3$ in the reaction product progressively increases until these products may become together the major products of the reaction.

As pointed out previously, the isomer $\text{CF}_2\text{ClCCl}_2\text{I}$ is an excellent chain transfer agent or telogen in telomerization reactions involving olefins such as $\text{CF}_2=\text{CFCl}$ and $\text{CF}_2=\text{CF}_2$. When this isomer is used as a telogen with these olefins, it is possible to control the molecular weight or chain length of the telomers so as to obtain high yields of desired narrow ranges of molecular weights merely by selection of the olefin:telogen iodide molar ratio, the number of olefin units in the telomer chain closely ap-

proximating the olefin:iodide ratio in the reaction mixture. Such telomerization reactions, employing the isomer $\text{CF}_2\text{ClCCl}_2\text{I}$ are described in detail in the co-pending application Serial No. 756,491, filed August 21, 1958, and now abandoned, of Murray Hauptschein et al. entitled "Halogenated Organic Compounds."

In contrast, the isomer $\text{CCl}_3\text{CF}_2\text{I}$ is a relatively poor chain transfer agent in such telomerization reactions. For this isomer, considerably higher temperatures are required to obtain any telomerization at all, and the telomers formed tend to vary over wide ranges of molecular weights, from low molecular weight liquids of comparatively little utility to mainly high molecular weight solids likewise of limited utility, rather than the desired high yields of intermediate molecular weight products of an oily character. In addition, such telomers that are formed with the isomer $\text{CCl}_3\text{CF}_2\text{I}$, e.g. telomers of the formula $\text{CCl}_3\text{CF}_2(\text{CF}_2\text{CFCl})_n\text{I}$ have the disadvantage that the telomer terminates in a CCl_3- end group which has considerably lower chemical and thermal stability than a CF_2Cl end group produced by the isomer $\text{CF}_2\text{ClCCl}_2\text{I}$, and are far less useful for transformation to surface-active agents.

This application is a continuation-in-part of copending application Serial No. 762,708, filed September 23, 1958, and now abandoned.

We claim:

1. A method for preparing the iodide $\text{CF}_2\text{ClCCl}_2\text{I}$ comprising the step of reacting $\text{CF}_2=\text{CCl}_2$ with iodine monochloride at a temperature of from -20° C . to $+15^\circ\text{ C}$.
2. A method in accordance with claim 1 in which said reaction is carried out at a temperature of from -10° C . to $+10^\circ\text{ C}$.
3. A method for preparing the iodide $\text{CF}_2\text{ClCCl}_2\text{I}$ comprising the step of reacting $\text{CF}_2=\text{CCl}_2$ with iodine monochloride at a temperature of -20° C . to $+15^\circ\text{ C}$. in the absence of iron in a form which is chemically attacked by the reactants or the reaction products.
4. A method in accordance with claim 3 in which said reaction is carried out at a temperature of from -10° C . to $+10^\circ\text{ C}$.
